UNITED STATES PATENT OFFICE.

HARVEY F. WALTER AND GEORGE R. MCNEELY, OF KINSTON, NORTH CAROLINA.

CARBONATING APPARATUS.

Application filed March 1, 1922. Serial No. 540,353.

To all whom it may concern:

Be it known that we, HARVEY F. WALTER and GEORGE R. MCNEELY, citizens of the United States, residing at Kinston, in the 5 county of Lenoir and State of North Carolina, have invented a new and useful Carbonating Apparatus, of which the following is a specification.

This invention aims to provide novel 10 means for controlling the flow of gas and water, for the purpose of providing a carbonated drink.

In the drawings:—Figure 1 shows in elevation, a device constructed in accordance 15 with the invention, parts appearing in section; Figure 2 is a sectional detail of the valve mechanism; Figure 3 is a section of the valve, taken at right angles to the showing of Figure 2; Figure 4 is a diagram illustrating the position of the parts when the valve 20 is closed; Figure 5 is a diagram showing the position of the parts when a large stream of carbonated water is being discharged; Figure 6 is a diagram showing the positions of 25 the parts when a small stream of water is being discharged; and Figures 7, 8 and 9 are diagrams illustrating the valve in different positions with respect to certain of the ports.

In carrying out the invention, there is 30 provided a water receiver 1, including a receiving compartment 2 and a delivery compartment 3. Water is discharged through a pipe 4 into the compartment 2. A check valve 5 is disposed between the compartments 3 and 2 and closes toward the compartment 2. Mixing chambers 6, 7 and 8 are provided. A pipe 9 connects the bottom of one mixing chamber with the top of the mixing chamber next adjacent thereto. A 35 pipe 10 leads from the chamber 8.

A conduit 11 connects the top of the chamber 6 with the intermediate portion of the delivery compartment 3. In the conduit 11, a receptacle 12 is disposed, a valve 14 being 40 located in the receptacle, the valve closing toward the delivery compartment 3. In the top of each of the chambers 6, 7 and 8, a sleeve 18 is placed, the sleeve carrying an upper screen 19, a lower screen 20, and an 45 intermediate frame 21, a mixing wheel 22 being journaled in the frame. A sleeve 15 is disposed in the lower end of each of the compartments 6, 7 and 8 and carries an upper screen 16 and a lower screen 17. The 50 function of the wheel 22 is to secure a thorough admixture of water and gas, and the

screens 17, 16, 20 and 19 contribute to this result.

A valve casing 23 is provided and has a main spout 24 supplied with a relatively 50 large bore 25 wherein a screen 26 is located. The numeral 27 marks a gas supply pipe communicating with a port 28 in the valve casing 23. A port 29 is fashioned in the casing 23 and is located opposite to the port 28. The port 29 communicates with a pipe 30 discharging into the receiver 6 intermediate the ends thereof. A port 31 is formed in the casing 23 and is spaced from the ports 28 and 29, circumferentially of the 70 casing. The pipe 10 leads to the port 31. A port 33 is formed in the casing 23 and is spaced circumferentially from the port 29. The port 33 communicates with a pipe 34 connected to the top of the delivery compartment 3 of the water receptacle 1. A port 48 is fashioned in the casing 23 and is spaced from the port 31 circumferentially of the 75 casing. The port 48 communicates with an auxiliary spout 46 located in the bore 25 of the main spout 24 and extended through the screen 26. A port 56 is formed in the casing 23 and is spaced from the port 48, circumferentially of the casing, the port 56 communicating with the bore 25 of the main 80 spout 24. A port 45 is constructed in the casing 23 and is spaced circumferentially of the casing from the port 56, the port 45 communicating with the bore 25 of the main 85 spout 24.

A valve 35 is mounted to rock in the casing 23 and is controlled by a handle 51. The valve 35 has an L-shaped channel 36 including a branch 37 and a branch 38 disposed at an angle thereto, the branch 38 having an 90 extension 50 prolonged circumferentially of the valve and the branch 37 having an extension 49 prolonged circumferentially of the valve. An L-shaped channel 40 is formed in the valve 35 and includes a relatively long circumferential branch 41 and a shorter branch 42. There is a channel 39 in the valve 35, disposed by the side of the branch 41 of the channel 40 and having a lateral branch 47.

Suppose that the valve 35 is in closed position, as indicated diagrammatically in Figure 4, the parts being so arranged that no carbonated water can flow through the bore 25 of the spout 24 or through the auxiliary spout 46. The port 28 registers with the branch 37 of the channel 36, and the

port 33 registers with the branch 38 of the channel 36. Gas flows through the pipe 27, through the port 28, through the branch 37 of the channel 36 through the branch 38, 5 through the port 33, through the pipe 34, and into the delivery compartment 3 of the water receptacle 1, the valve 5 being closed, and the water in the compartment 3 flowing through the conduit 11, the valve 14 open- 10 ing, and the water entering the mixing chambers 6, 7 and 8. The port 31 is out of registration with the channel 39, and there is no flow of carbonated water through the channel 39, its branch 47, the port 48 and 15 the auxiliary spout 46. Neither is there any flow through the port 56 to the bore 25 of the spout 24. Consequently, no carbonated water is delivered.

Suppose, however, that the valve 35 is 20 turned until the parts assume the positions shown in Figures 5, 7 and 8. Under such circumstances, there will be a delivery of carbonated water through the main spout 24. The port 28 registers with the branch 25 37 of the channel 36. The port 29 registers with the branch 38. The port 33 registers with the branch 41 of the channel 40, and the port 45 registers with the branch 42 of the channel 40. The port 31 registers with 30 the channel 39, and so does the port 56. Gas traverses the pipe 27, the port 28, the branch 38 of the channel 36, the port 29, and the pipe 30, the mixture of water and gas traversing the receiver 6, the pipes 9, the 35 receivers 7 and 8, the pipe 10, the port 31, the channel 39, the port 56 and the bore 25 of the main nozzle 24 the carbonated water being discharged in a relatively large stream through the main nozzle. A vent 40 is established through the bore 25 of the main spout or nozzle 24, the port 45, the branch 42 of the channel 40, the branch 41, the port 33 and the pipe 34, the valve 5 opening, water flowing from the pipe 4 into the 45 receiving compartment 2, and from thence into the delivery compartment 3, the valve 14 being held closed by the pressure of gas which is delivered back into the receptacle 12, through the conduit 11.

50 Suppose that the parts are arranged as depicted in Figures 6 and 9. Under such circumstances, a small stream of water, duly carbonated, will be discharged through the

auxiliary spout 46. The port 28 registers with the extension 49 of the branch 37 of 55 the channel 36, and the port 29 registers with the extension 50 of the branch 38. The port 33 is still in registration with the branch 41 of the channel 40, but the port 45 is out of registration with the branch 42. 60 The port 31 registers with the channel 39, and the port 48 registers with the branch 47 of the channel 39. Gas traverses the pipe 27, the port 28, the extension 49 of the channel 37, the branch 38, its extension 50, 65 the port 29, and the pipe 30, gas being delivered into the receivers, as hereinbefore explained. The carbonated water, passing from the receiver 8, traverses the pipe 10 and passes through the port 31 into the channel 70 39 and its branch 47, the water moving through the port 48 into and through the small auxiliary spout 46, and being discharged with force, in a reduced stream, through the said spout. 75

When the valve 35 is rotated by means of the handle 51 until the parts assume the positions of Figure 4, the supply of carbonated water to the drinking glass is cut off. 80

What is claimed is:—

In a device of the class described, a delivery compartment; a mixing chamber; a conduit connecting the mixing chamber with the compartment; a source of liquid supply 85 for the compartment; a valve in the compartment and closing toward said source; a valve in the conduit and closing toward the compartment; a main outlet for the liquid to be dispensed; an auxiliary outlet 90 for the liquid to be dispensed; means for placing the outlets one at a time in communication with the mixing chamber; a source of gas supply; means for placing the source of gas supply in communication with the chamber when either outlet is open; means for placing the source of gas supply 95 in communication with the compartment when both outlets are closed; and means for venting the compartment when one outlet is open. 100

In testimony that we claim the foregoing as our own, we have hereto affixed our signatures.

HARVEY F. WALTER.
GEORGE R. McNEELY.
